UNITED STATES PATENT OFFICE

PAUL NAEHER, OF CHICAGO, ILLINOIS, ASSIGNOR TO B. F. GUMP COMPANY, OF CHICAGO,
ILLINOIS, A CORPORATION OF ILLINOIS

BARREL PACKER

Application filed September 17, 1928. Serial No. 306,568.

This invention relates to machines for compacting materials in barrels during the time that the barrels are being filled. An object of the invention is to provide such a machine having a rocking frame and a barrel supporting platform positioned centrally of the frame and means for actuating the same whereby a backward throw to opposite sides of the barrel is effected for compacting the material therein.

With the above and other objects in view, the invention consists in certain novel features of construction, combinations and arrangements of parts as will be more fully described and particularly pointed out in the appended claims.

In the accompanying drawings:

Figure 1 is a side elevation of a barrel packer made in accordance with the present invention;

Figure 2 is an end elevation of the machine shown in Figure 1 partly in section;

Figure 3 is a section taken on line 3—3 of Figure 2;

Figure 4 is a section taken on line 4—4 of Figure 1;

Figure 5 is a diagram illustrating in an exaggerated manner the movement imparted to the barrel.

In general the machine comprises a supporting frame, a rockable frame mounted thereon and provided with a barrel supporting platform located centrally thereof. The arrangement is such that upon the actuation of the rockable frame, there will be imparted to the frame and platform, similar gyratory motions upon opposite sides of the center thereof but opposite in phase. The resulting peculiar elliptical shaped motion has a backward throw to opposite sides of the barrel and is very effective in securing extremely hard packing.

In detail the machine comprises a bed frame 1 having mounted thereon a rocker frame 2 provided centrally thereof with a barrel supporting platform 3, this platform in turn supporting an annular barrel plate 4 adapted to position the barrel upon the platform by fitting within the chine thereof. The bed frame is provided with spaced side

members 5 upon which are suitably journaled crank shafts 6 and 7 respectively. Inwardly of the side members 5, the shaft 6 is provided with eccentric portions or cranks 8 mounted in bearings 9, said bearings being 55 directly secured to the side bars 10 of the rocker frame 1. The shaft 7 is also provided with eccentric portions 11 suitably journaled in bearings 12. These bearings however, are not directly secured to the rocker frame as 60 in the case of the bearings 9 but instead are provided with links or extensions 13 projecting through openings 14 in the side bars 10 and pivotally connected to the side bars 65 below the openings by means of pins 15 suitably secured in the bed frame 1.

As shown, in Figure 4, a pair of intermeshing gears 16 and 17 are mounted on concentric portions of the shafts 6 and 7 respectively between the eccentric portions 8 70 and 9, these gears being adapted to rotate in the direction indicated by the arrows in Figure 3. The shaft 6 extends outwardly beyond the bed frame upon one side thereof and is provided with a drive pulley 18 by 75 means of which motive power is supplied to the machine.

For securely retaining a barrel upon the platform 3, during the filling and packing operation the following construction is provided: A pair of vertical standards 19 are supported at opposite ends of the rocker frame 2, each standard having adjustably secured thereto at its upper end, a lever bracket 20. Secured to each bracket is a 80 lever handle 21 which is provided intermediate its ends with a lateral projection 22 having an opening 23 extending therethrough and within which is pivotally mounted the upper end of a link 24. The lower end of each link is pivotally secured to an annular barrel clamp member 25, this member having secured to its lower face, an angular ring-shaped hoop 26 which is adapted to engage the upper rim or chine of the barrel shown in dotted lines. The member 25 is provided at opposite sides thereof, with hollow lugs 27 each one of which embraces one of the standards 19 and is adapted to slide 85 thereon to guide the member in its up and 90 down movement. The standards 19 are provided with a 95 slot 28 through which the member 25 may be moved. The standards 19 are secured to the bed frame 100 by bolts 29.

down movement. Each lever handle 21 is provided with a latch handle 28 connected to a pawl 29 by means of a pull rod 30 while the lever brackets 20 are provided with ratchets 30 adapted to cooperate with the pawls to retain the lever handles in clamped position. A tie rod 31 suitably connects the lever handles and is adapted to be grasped by the operator when a barrel is to be clamped in operative position.

For retaining the member 25 in its upper inoperative position, there are provided a pair of spring pressed holders 32 secured to the brackets 20 and adapted to engage the lugs 27 and prevent the same from dropping down on the standards. In Figures 1 and 3 the lugs and member 25 are shown in their lowermost positions. For effecting an adjustment of the member 25, the upper end 20 of each standard is screw threaded to receive spaced adjusting nuts 34, the bracket 20 being positioned between these nuts and having only a sliding contact with the standard. When it is desired to adjust the member 25 25 for different sizes of barrels, it is only necessary to rotate the nuts upon the threaded portions of the standards to the desired position of adjustment.

With the machine as thus described, the operation is as follows: A barrel to be packed with material is placed upon the platform 3 and is positioned centrally thereof by means of the barrel plate 4. Assuming that the member 25 has been correctly adjusted to the size of the barrel, the holders 32 are pulled outwardly releasing the lugs 27. The tie rod 31 is then grasped by the operator and pushed downwardly until the ring 26 tightly engages the upper rim of the barrel, the pawl and ratchet arrangement preventing any upward movement of the lever handles and consequently of the member 25; thus a secure clamping action is effected which insures the retention of the barrel 45 upon the platform 3. The machine is then actuated from a suitable source of power (not shown) and at the same time the material to be packed (not shown) is fed into the top of the barrel. Because of the construction of the bed and rocker frames and the arrangement of the gears and eccentrics, the shafts will rotate in opposite directions, imparting to the rocker frame and to the platform, similar but out of phase gyratory motions upon opposite sides of the center thereof. This will result in a backward throw of the material to opposite sides of the barrel along the lines of the standards and will effectively pack the material as it is being fed into the barrel. After the barrel has been completely filled and packed, the latch handles are actuated to release the pawls 29 from the racks 30 and permit the lever handles and the member 25 to be raised to their inoperative position, whereupon the barrel

may be quickly removed and an empty one replaced upon the platform 3.

From the foregoing it will be apparent that I provide a novel form of machine for packing materials in barrels and adapted to be actuated in such a manner as to quickly and completely compact the material in the barrel during the filling operation.

As illustrated in Figure 5, the eccentrics 8 and 11 of the shafts 6 and 7 are held in opposite phase by the intermeshing gears 16 and 17 which gears also cause said shafts to rotate in opposite directions, one clockwise and the other counter-clockwise. This will cause one eccentric to lift its side of the platform while the other eccentric depresses the opposite side of the platform, thereby imparting a rocking movement as well as a lateral oscillation. The total effect is to cause a close packing of the granular material within the barrel.

What I claim as my invention is:

1. A machine for compacting materials in barrels comprising a rockable frame, a barrel supporting platform positioned centrally of said frame, means for retaining a barrel in operative position upon said platform, including a member supported above said platform and adapted to engage the upper end of said barrel, and means for rocking said frame for imparting similar out of phase gyratory movements to said platform upon opposite sides of the center thereof.

2. A machine for compacting materials in barrels comprising a rockable frame, a barrel supporting platform positioned centrally of said frame, means for retaining a barrel in operative position upon said platform including a member movably supported above said platform and adapted to engage the top rim of said barrel, and means for rocking said frame for imparting similar out of phase gyratory movements to said platform upon opposite sides of the center thereof.

3. A machine for compacting materials in barrels comprising a rockable frame, a barrel supporting platform positioned centrally of said frame, a bearing on said platform for engaging the chine of the barrel, means for rocking said frame, and means for retaining a barrel in operative position upon said platform including a pair of standards supported at opposite ends of said frame, and a barrel clamp member slidably between said standards and adapted to engage the upper end of the barrel.

4. A machine for compacting materials in barrels comprising a rockable frame, a barrel supporting platform positioned centrally of said frame, means for rocking said frame, and means for retaining a barrel in operative position upon said platform including an annular bearing for engaging the chine, a pair of standards supported at opposite ends of said frame, brackets secured to said standards, lever handles pivoted to said brackets, and a

- barrel clamp member connected to said levers and adapted upon a downward movement thereof to engage the upper end of the barrel.
5. A machine for compacting materials in barrels comprising a rockable frame, a barrel supporting platform positioned centrally of said frame, means for rocking said frame, and means for retaining a barrel in operative position upon said platform including an annular bearing for engaging the chine, a pair of standards supported at opposite ends of said frame, brackets adjustably secured to said standards, a barrel clamp member slidable upon said standards, lever handles pivotally connecting said brackets and member and adapted to be moved downwardly to place said member in clamping engagement with said barrel.
6. A machine for compacting material in barrels comprising a rockable frame, including a platform, a bearing on said platform for engaging the chine of a barrel, a vertical standard rising from said platform, a member for engaging the upper end of the barrel adjustable on said standard, actuating means for said member to clamp the barrel, a pair of shafts arranged on opposite sides of the center of said platform and axis of the barrel, means for rotating said shafts at equal angular speeds in opposite directions, eccentrics on said shafts arranged in opposite phase, a bearing engaging one of said eccentrics and directly connected to said rockable frame and a bearing engaging the other of said eccentrics having a pivotal link connection with said frame.

In testimony whereof I affix my signature.
PAUL NAEHER.
